UNITED STATES PATENT OFFICE.

ASA G. DAILEY, OF DETROIT, MICHIGAN.

CATTLE-GUARD.

SPECIFICATION forming part of Letters Patent No. 548,430, dated October 22, 1895.

Application filed February 7, 1895. Serial No. 537,590. (No model.)

To all whom it may concern:

Be it known that I, ASA G. DAILEY, a citizen of the United States, residing at Detroit, in the county of Wayne and State of Michigan, have invented certain new and useful improvements in Cattle-Guards, of which the following is a specification, reference being had therein to the accompanying drawings.

The invention relates to the construction of a sheet-metal cattle-guard having teeth struck up from the body thereof in such a manner as to provide a substantially even distribution of the teeth and leave a web of substantially even strength at all parts, all as more fully hereinafter described.

The invention consists in the peculiar construction of a metallic surface-guard composed of metal plates apertured by punches or dies and the metal forced upward in such a manner as to produce the greatest number of projections from a given plate, at the same time producing a uniform spacing between the apertures.

In the present state of the art cattle-guards have been manufactured in sections, each section being a single sheet-metal plate having struck from the body thereof points or fins, these points or fins being made in many different forms. The arrangement of these apertures, however, has not been such as to arrange the points sufficiently near together and of sufficient height to destroy the footing of animals. The spacing between the points in such prior construction has not been uniform, the result of which is to produce a guard which is abnormally weak at points and having unnecessary strength at others, thus not utilizing the metal to advantage. In my device I overcome these objectionable features by forming triangular apertures in the guard, so arranged in relation to each other that a maximum number of points can be struck up in a given plate and a uniform spacing or web between the apertures produced, which greatly increases the strength and life of a guard.

In the drawings, Figure 1 is a perspective view of a portion of one section of a guard of my invention, in which the teeth or points are in the form of isosceles triangles. Fig. 2 is a top plan view of the same. Fig. 3 is a perspective view of the guard, showing the teeth in the form of equilateral triangles. Fig. 4 is a

top plan view thereof, and Fig. 5 is a vertical section at right angles to the line of track. Fig. 6 is a plan view showing another arrangement. Fig. 7 is a side elevation of a portion of the section shown in Fig. 1.

A represents the metal plates, from one of which I form each section of my cattle-guard. From each plate I strike up teeth or points B at substantially right angles to the plate, leaving the perforations G in the body of the plate. I preferably arrange these teeth as shown in Fig. 1, shaped as isosceles triangles arranged in transverse rows, the alternate teeth of each row being oppositely arranged—that is, the first tooth of the first row D having its base adjoining the end of the plate, while the next tooth E has its base in the second row diagonally opposite the base of the first tooth and parallel thereto, as plainly shown in Fig. 1, the teeth being struck up to stand upon the base of each triangle.

The teeth are separated laterally by the strip F, and the rows of teeth are separated by the transverse strips G', the strips F and G' forming an even web over the entire structure, which supports the teeth. These teeth thus arranged would be arranged in rows in line with the base of the teeth. To effect a perfectly even arrangement of the teeth, I bend the teeth slightly from the perpendicular, as shown in Fig. 7, so as to space the teeth equally at all parts of the plate.

I may change the form to that shown in Fig. 4, in which the teeth are shaped as equilateral triangles arranged in rows H I, the teeth in the row H being struck up on the base a, while those in row I are struck up on base b. This effects a more even distribution of the points without bending and leaves the same web as in the construction previously referred to.

In Fig. 6 I have shown two teeth struck up together or in pairs, with the strip F between the pairs instead of between each single tooth.

What I claim as my invention is—

1. A cattle guard section formed of a sheet of metal, having pointed teeth alternately struck up in different directions and in rows, to leave the tooth spacing strip F and the row spacing strips G' of substantially uniform width.

2. In a cattle guard section formed of a sheet

of metal triangular teeth alternately struck up therefrom in different directions and in rows, and a web of substantially uniform width left between the teeth and between the rows, substantially as described.

3. A cattle guard section formed of sheet metal triangular teeth struck up therefrom in separated rows, the apertures thus formed being alternately on opposite sides of the base

of the teeth, the teeth being bent to be separated substantially equal distances.

In testimony whereof I affix my signature in presence of two witnesses.

ASA G. DAILEY.
